UNITED STATES PATENT OFFICE.

ADAM G. MAHLER, OF MEDFORD, NEW YORK.

BUILDING-BLOCK.

No. 900,753.

Specification of Letters Patent.

Patented Oct. 13, 1908.

Application filed November 21, 1907. Serial No. 403,154.

To all whom it may concern:

Be it known that I, ADAM G. MAHLER, a citizen of the United States, and a resident of Medford, in the county of Suffolk and State of New York, have invented a new and Improved Building-Block, of which the following is a full, clear, and exact description.

This invention relates to building blocks such as are used in the construction of walls for buildings.

The object of the invention is to produce a block of simple form which can be quickly laid in constructing walls, and which is provided with improved means for connecting or bonding the adjacent blocks.

A further object of the invention is to provide means for facilitating the application of plaster on the inner side of the wall, and to provide an arrangement for bringing about a free circulation of the air from the interior of the wall to the outside, without allowing the admission of rain.

A further object of the invention is to provide the block with means for making the horizontal joints between the blocks water-proof.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a vertical section through a portion of a wall formed of building blocks constructed according to my invention; this section is taken on the line 1—1 of Fig. 4; Fig. 2 is a vertical section through the same wall; this view is a cross section on the line 2—2 of Fig. 4; Fig. 3 is a perspective of a building block constructed according to my invention; and Fig. 4 is a plan showing a short portion of a wall constructed of blocks formed according to my invention, certain parts being shown in cross section.

Referring more particularly to the parts and especially to Fig. 3, 1 represents the block; it is of substantially rectangular form, presenting two chambers 3 and 4, which extend completely through the block from the upper face to the lower face. These chambers are separated by a transverse bar 5, which connects the outer wall 6 of the block with the inner wall 7. The end walls 8 of the block are depressed; that is, they are off-

set inwardly so that at each end of the block projecting ribs or shoulders 9 are formed at its vertical edges. In this way a recess is formed in the ends of the block, and in the lower portion of this recess the end wall is provided with an outwardly projecting boss 10 of triangular form. The outer face of this boss is substantially flush with the ribs or shoulders 9, and the face of the triangular boss lies in the plane of the lower face of the block. The boss is of less width than the recess in the end of the block, so that gaps or spaces 11 are formed at each side of the boss, as illustrated in Fig. 3.

The inner sides of the shoulders 9 are preferably provided with beveled faces or edges 12. On the upper edge of the outer wall of the block a longitudinally disposed tongue 13 is formed, and on the lower edge 75 of this wall a corresponding groove 14 is formed, the arrangement being such that when the block is laid upon another block, the tongue and groove interlock with each other, as illustrated in Fig. 2. In laying the 80 blocks to form a wall, they are laid one upon the other as illustrated in Figs. 1 and 2. Two adjacent blocks lying in the same horizontal row come face to face, so that the outer faces of the bosses 10 abut against each other, as illustrated in Fig. 1. No mortar or concrete is laid between these meeting faces. However, when the two blocks come together end to end as illustrated, the depressed end walls of the blocks come together so as to 85 form a bonding space 15, as will be readily understood, and in this bonding space concrete 16 is placed. This concrete hardens and extends in one continuous piece from the lower row to the next row above, and in this 90 way a firm bond or connection is made between two consecutive rows. When the blocks are laid in horizontal rows in the usual manner, that is, in staggered relation, the ends of the blocks in an upper row meet 95 over the bar of a block in the row below. The bases completely bridge the space above the bar between the side walls so that the cement bond at this point is supported in spite of the fact that the bar 5 is of reduced 100 width, as shown, and has a depressed face which could not effectively support the cement.

In order to provide for the circulation of air in the chambers 3 and 4, the outer wall 6 110 of each block is provided with openings 17 which communicate respectively with these

chambers. These openings taper toward the inner side of the outer wall 6 of the block, and incline upwardly toward the interior of the block, as illustrated in Fig. 2. From this arrangement it becomes impossible for rain to be driven into the interior of the block by the wind.

In order to facilitate the application of mortar on the inner side of the wall after it has been erected, I form each block in the mold with a veneer or facing 18 of plaster of paris, as illustrated in Fig. 2 and 3. This veneer is quite thin, but adheres tightly to the face of the block and presents a neat appearance. It also enables plaster to be applied with facility on the inner face of the wall, so that the cracks between the blocks will become hidden and the interior of the wall will present substantially the same appearance as an ordinary plaster wall. The blocks are preferably molded of concrete or similar material.

Having thus described my invention, I claim as new and desire to secure by Letters Patent:

A building block having end walls with vertically disposed ribs at the sides thereof, and bosses with tapered side edges formed on said end walls near a horizontal face of said block, the outer faces of said bosses being substantially flush with the outer faces of said ribs whereby a bonding space is formed between said ribs and said bosses adapted to receive concrete to bond adjacent horizontal rows, the said end walls between said ribs and said bosses being flat and depressed.

In testimony whereof I have signed my name to this specification in the presence of two subscribing witnesses.

ADAM G. MAHLER.
